UNITED STATES PATENT OFFICE.

CHARLES M. LEHMAN, OF MIDDLEBURY, INDIANA.

TRACE-FASTENING DEVICE.

No. 847,417.

Specification of Letters Patent.

Patented March 19, 1907.

Application filed December 7, 1906. Serial No. 346,795.

To all whom it may concern:

Be it known that I, CHARLES M. LEHMAN, a citizen of the United States, residing at Middlebury, in the county of Elkhart and State of Indiana, have invented new and useful Improvements in Trace-Fastening Devices, of which the following is a specification.

My invention pertains to devices for fastening traces on swingletrees; and it consists in the peculiar and advantageous construction hereinafter described and claimed.

In the accompanying drawings, forming part of this specification, Figure 1 is a view illustrating in elevation a portion of a swingletree equipped with my novel device and also illustrating in transverse section a trace held by the device on the swingletree and further illustrating by dotted lines the position in which the device is placed relative to the swingletree to permit of a trace being placed on or removed from the swingletree. Fig. 2 is a perspective view of the portion of the swingletree bearing the fastening device, the trace being shown by dotted lines. Fig. 3 is a plan view showing the trace secured through the medium of the fastening device on the swingletree, and Fig. 4 is a transverse section taken in the plane indicated by the line 4-4 of Fig. 3 looking outward.

Similar letters designate corresponding parts in all of the views of the drawings, referring to which—

A is a swingletree, which is preferably of the well-known conventional form.

B is a trace, which is provided with an eye b and is otherwise of the ordinary type.

C is my novel device for fastening the trace on the swingletree, and D is the screw which forms a pivot for and effects connection of the fastening device C to the swingletree.

The fastening device C is formed of one piece of suitable metal and comprises an intermediate portion c, having a transverse aperture for the passage of screw D and also having a countersink d in its outer side to receive the head of the screw, a trace-retaining arm e, reaching from said intermediate portion c, and an arm f, which is disposed at a right angle to the retaining-arm e and is preferably of greater length than the said arm e in about the proportion shown in order to afford leverage and in that way render adjustment of the fastening device more easy.

At its free end—*i. e.*, its end remote from the intermediate portion c—the arm f of the fas-

tening device is provided with an enlargement g. This enlargement g is designed to prevent the trace B from slipping inward on the swingletree to a point where said trace is 60 clear of the arm f, and it is provided with an extension h, disposed laterally to arm f and designed by bringing up against the side of the swingletree to hold the arm f against downward movement beyond the position 65 shown in Fig. 1.

In practice my novel fastening device is arranged against and connected to the edge of the swingletree, and when it is desired to place the trace on the swingletree the fastening device is swung to the position shown by dotted lines in Fig. 1, so that its retaining-arm e lies parallel to the edge of the swingletree, while its arm f extends upright. The trace is then shoved on the end portion of the 75 swingletree and the arm e of the fastening device until it rests adjacent to the intermediate portion c of the device, when the device is swung to the position shown by full lines in Fig. 1. On this being done it will be observed that the arm f of the fastening device will rest in the eye of the trace and will be retained by the trace against casual movement away from the edge of the swingletree, and consequently the retaining-arm e 80 will be held in an upright position, in which position it will preclude casual movement of the trace off the swingletree. To remove the trace from the swingletree, it is simply necessary to position the trace adjacent to 85 the intermediate portion c of the fastener and then move the fastener to the position shown by dotted lines in Fig. 1, when the trace may be readily moved off the arm e and the end portion of the swingletree. 90

It will be gathered from the forgoing that my novel fastening device is simple and inexpensive in construction and light in weight and that it is calculated to enhance rather than detract from the finished appearance of a 100 swingletree. 95

Having described my invention, what I claim, and desire to secure by Letters Patent, is—

The combination of a swingletree, and a 105 trace-fastening device arranged to swing vertically alongside one edge of the swingletree and comprising an intermediate portion pivotally connected to the edge of the swingletree, an arm adapted in one position of the 110 device to extend upward from the intermediate portion and retain a trace on the swing-

tree and in another position of the device to rest parallel to the edge of the swingletree, an arm extending from the intermediate portion and at a right angle to the retaining-arm and arranged when said retaining-arm is upright to lie parallel to the edge of the swingletree, and a lateral enlargement *g* on said arm, arranged to hold the trace against undue inward movement and having an extension *h* arranged to bring up against the usual upper

side of the swingletree to hold the arm against undue downward movement.

In testimony whereof I have hereunto set my hand in presence of two subscribing witnesses.

CHARLES M. LEHMAN.
